UNITED STATES PATENT OFFICE.

PAUL A. NEWMAN, OF PHILADELPHIA, PENNSYLVANIA, ASSIGNOR TO LEEDS & NORTHRUP COMPANY, OF PHILADELPHIA, PENNSYLVANIA, A CORPORATION OF PENNSYLVANIA.

FUSE.

Application filed October 30, 1924. Serial No. 746,749.

My invention relates to fuses utilized for causing rupture of electric circuits upon attainment of predetermined thermal conditions, and relates more particularly to effecting circuit rupture upon attainment by a fusible element of a predetermined temperature due to the combined or joint effects of heat produced within the fusible element by the electric current traversing it and of heat absorbed by the fusible element.

In accordance with my invention, the fusible element, as a fuse wire or equivalent, is so spaced from or disposed with respect to a hot zone or member that it does not partake of the temperature thereof, but attains, due to heat conducted, radiated or otherwise transferred from the hot zone or member, a lower temperature which, however, is augmented by the heat developed within the fusible element itself by the electric current traversing it, whereby the fusible element attains a fusing temperature, causing circuit rupture, when the hot zone or member attains a predetermined temperature, which, however, is or may be different from the temperature at which the fusible member melts.

More particularly in accordance with my invention, the fusible member is included in circuit with the resistor or other heating device of any heating structure, as a furnace, oven, electric heater or the like, and is disposed adjacent or in contact with a wall of the heating device or furnace through which it absorbs heat and attains a temperature lower than the maximum temperature of the heating device or furnace, and the cross section of the fusible element is so proportioned that the current traversing it develops sufficient heat further to raise its temperature, causing it to attain its fusing temperature, which may be somewhat less than, equal to or greater than the maximum temperature of or within the heating device or furnace, and by preference, the temperature change of the fusible element due to the current traversing it is relatively small compared to the temperature change effected by the heat absorbed from the heating device or furnace, whereby the fuse will melt or blow at substantially the same temperature of the heating element or furnace, though the cur-

rent traversing the fusible element may have widely different magnitudes.

Further in accordance with my invention, it is preferred that the fusible element be composed of a material having a substantial positive temperature co-efficient of resistance, whereby its rise in temperature due to heat absorbed from the hot zone or member increases its resistance, thereby increasing the heat developed within the resistance element itself by the current traversing it, whereby as the temperature of the hot zone or member increases, the temperature of the fusible element will increase due both to such increase in temperature of the hot zone or element and also to the increase in the heat generated within the fusible element itself by the current traversing it, to the end that as the fusing temperature is approached the two sources of heat co-operate in effecting increase in the rate of approach to the fusing temperature.

My invention resides in the method and features of structure and combination of the character hereinafter described and claimed.

For an understanding of my method and for an illustration of one of the various forms my apparatus may take, reference is to be had to the accompanying drawing, in which:

Fig. 1 is a horizontal sectional view taken on the line 1—1 of Fig. 6.

Fig. 2 is a vertical sectional view taken on the line 2—2 of Fig. 1.

Fig. 3 is a cross sectional view taken on the line 3—3 of Fig. 2.

Fig. 4 is a cross sectional fragmental view taken on the line 4—4 of Fig. 2.

Fig. 5 is a cross sectional view taken on the line 5—5 of Fig. 2.

Fig. 6 is a schematic sectional view of an electric furnace showing the relation between the fusible element and the heating element.

Referring to the drawing, more particularly Fig. 6, F represents an electrically heated furnace comprising the shell 1, of sheet metal or equivalent, within which is disposed the hollow tubular heating or resistor element 13 resting upon the bottom member 2 and closed at its upper end by the removable lid or cover 3. Surrounding the member 13 within the shell 1 is a filling of

suitable mineral matter or other material, preferably of poor heat conductivity. Disposed within the wall of the member 13, of ceramic or the like, is the helically disposed 5 resistance wire 14 traversed by current which causes the evolution of heat for heating purposes, the current being regulable by a rheostat 4, or equivalent means, to effect various 10 rates of heat production and various temperatures within the heating chamber C, within which may be disposed a thermo-couple 11, or any other suitable temperature-responsive 15 means for temperature measurement or control. As indicated, the fusible element 12 may be connected in circuit with the heating resistance 14, or equivalent heat-producing means.

The fuse structure comprises the member or block 15, of lava, porcelain or other equivalent or suitable material, having at its opposite ends the recesses or cavities 16 and 17. The member 15 is received at its one end within the exteriorly threaded tubular member 18, of iron or other suitable material, 25 having at 18^b a shoulder against which the end of the member 15 abuts. The members 15 and 18 project through an opening in the furnace shell 1, on opposite sides of which are disposed the nuts or collars 19, 19 threaded 30 upon the member 18 and between which the shell is clamped, for holding the member 18 and the parts carried thereby in position. Disposed loosely within the member 18 is the block or member 18^a, of fibre or other suitable 35 insulating material, in which are disposed and held the blocks or inserts 24, of brass or other conducting material, having the transversely extending holes 26, into which extend the circuit conductors 27, by 40 which the fusible element 12 is brought into circuit. Threaded into the blocks 24 are the binding screws 28, whose heads are accessible through the apertures 29 in member 18^a, holding the conductors 27, which extend 45 through the oppositely disposed and longitudinally extending slots 20 in the member 18. Extending longitudinally through the member 15 is the slot 21, within which are disposed side by side the longitudinally extending 50 tubular members or beads 22, of porcelain or equivalent material, each abutting at its one end against a block 24. The fusible element 12 preferably consists of a conductor or wire of substantially constant cross section, though it will be understood that it may 55 be of changing or varying cross section. In the example illustrated, the fuse wire 12 extends through the members 22 and has at their right end a free or exposed portion 12^a, 60 which shall melt or blow, adapted to lie adjacent or against a wall or member 13 within or on the opposite side of which exists the temperature at whose attainment of a predetermined magnitude it is desired that the 65 fuse shall melt or blow. At its opposite ends

the fuse wire 12 extends into holes 30 in the blocks 24 and are clamped or held in the position indicated by screws 32, whose heads are accessible through the apertures 31 in the member 18^a.

70

Each of the members 22 is preferably provided with a second hole or channel in which is disposed a member or wire 25, as of constantan or other suitable material, threaded into a block 24, and serving to support or 75 carry the member 22, or in any event, to relieve the fuse wire 12 of at least a part of the weight of the member 22.

Threaded upon one end of the member 18 is the cap 33, within which is disposed the 80 spring 34 received in the groove 18^c of the member 18^a and thrusting the latter, the blocks 24, members 22 and the fusible element 12 toward the right, as viewed in Figs. 1 and 2, adjustment of the position of the cap 33 upon the member 18 serving to vary the pressure with which the fusible element 12^a engages the member 13. With a structure of the character described, a new fuse wire may be introduced by removal of the 85 cap 33 and subsequent withdrawal through the members 18 and 15, which remain in position, of the member 18^a, which carries the members 22 and the old or recently blown 90 fuse wire. By loosening the screws 32 the old fuse wire is removed and a new one inserted, and the parts then re-assembled to the 95 position indicated in Fig. 1.

100

The fusible element 12 may be of any suitable material, but by preference is of substantially pure silver or gold, and by preference of a material which has a substantial positive temperature coefficient of resistance. Even though silver or gold be used, the fuse 105 is inexpensive because of its small mass and the recovery of a portion of the fuse wire.

100

The cross section of the fusible element or fuse 12, particularly at the portion 12^a thereof which shall blow or fuse, may be anything suitable or desirable, and by preference is 110 such that the maximum operating current of the circuit will not fuse or blow it without the application of additional heat.

110

The cross section of the fusible element may be, and in some instances of my practice has been, such that even with the maximum furnace-heating current the rise in temperature above the ordinary temperature of the atmosphere has been so small that the fusible element could be touched with impunity.

115

Small cross section is further desirable to reduce the variations and effects due to variations in temperature drop through the heater or furnace wall, as 13, and the variations in 125 thermal contact between the fusible element and the furnace wall. By choosing a suitably small cross section notwithstanding the aforesaid variations in temperature drop and thermal contact, the fuse will melt or blow at 130

furnace chamber or heater temperatures which differ from each other as little as 25 degrees F., though the temperature of the heater or within the furnace chamber may 5 be of the order of 1000 or 1800 degrees F.

- It is further desirable that the portion 12^a be suitably remote from the blocks 24 and adjacent parts that the heat externally applied to the portion 12^a will encounter sufficient 10 thermal resistance along the wire 12 to prevent the blocks 24 and the adjacent parts from attaining a temperature which would cause their oxidation or deterioration. It is preferable these parts do not attain a 15 temperature exceeding that at which they may be touched by the hands of an operator in replacing a fuse notwithstanding the fact that the furnace or heating element is still at high temperature.

- 20 It is further desirable that the removable fuse element shall not comprise parts soldered, welded or similarly attached to the fuse wire proper, for there is likelihood, particularly under conditions of use herein described, particularly when the fusible element per se is short, of sufficient rise of temperature at the welded, soldered or other joint to cause melting or severance from the so applied terminals or parts.
- 25 One of the modes of operation of my system is as follows:

When the heating device or furnace is cold and is to be started, the current passing through the heating device proper, as resistance 30 14 or any other equivalent heat-producing means, is adjusted in magnitude, as by rheostat 4 or any equivalent means, to a suitable maximum, at which, however, the fuse 12 will not melt or blow. This effects maximum rate of development of heat, and as the temperature of the heating element 13 or within the chamber C approaches the desired magnitude, as determinable by the thermocouple 11, or equivalent, and associated temperature-indicating or measuring means, the current through the heating resistance 14 is reduced to such magnitude that thereafter a substantially constant desired temperature within the member 13 or chamber C will be 40 maintained. At such predetermined or desired temperature the fuse will not melt or blow, though it has been raised in temperature by heat absorbed and transmitted to it by or through the member 13. The temperature of the fuse wire, particularly at 12^a, due to the heat absorbed by it by conduction, radiation or otherwise from or through the member 13, and the heat generated within the fuse wire by the current traversing it, is 45 below that at which it will fuse or melt and open the circuit of the heating resistance 14. The temperature of the fuse wire 12^a is, however, preferably near its fusing point for the maximum desired or predetermined temperature of the member 13 or within the 50

chamber C. If, however, the current through the resistance 14 and fuse should increase, or if the temperature of or within the member 13 should increase, the temperature of the fuse wire will further rise and attain the 55 melting point, causing rupture of the circuit, and thereby prevent burning out of the resistance 14, or equivalent, and prevent undue rise of temperature within the chamber C.

When the fuse is of a material having a 60 positive temperature co-efficient of resistance, the rise in temperature of or within the member 13 beyond that for the maximum desired or predetermined temperature causes an increase of resistance in the fuse wire, with the 65 result that there is additionally liberated within it more heat by the current traversing it for a given current strength and a further increase if the current strength has increased, whereby the heating effect of the current and the heating effect of the member 13 or chamber C upon the fuse wire operate cumulatively near the fusing temperature of the fuse wire to bring it rapidly to fusing temperature and thereby open the circuit. 70

The temperature change of the fuse wire is preferably very largely due to the heat absorbed by it, and only to relatively small extent to the heat generated within it by the current traversing it. The temperature attained by the fuse wire, as at 12^a, due to absorbed heat, is lower than the maximum desired or predetermined temperature of or within the member 13 or chamber C, and, in a sense, the C^2R heat generated by the current in the fuse wire more or less compensates or makes up for the difference, whereby the fuse will melt when the predetermined desired or maximum temperature is exceeded. The mass or cross section of the fusible element is preferably made as small as possible, consistent with other circumstances, so that the fusible element may quickly respond to changes or rise in temperature and cause the desired operation of circuit rupture as and 80 when described promptly after the predetermined or desired maximum temperature within the chamber C or of the member 13 is exceeded. 100

The fusible element will blow and interrupt the circuit when the predetermined desired or maximum temperature is exceeded notwithstanding the fact that the current traversing it may have widely different values. For example, the fuse will blow for 110 practically the same temperature within the chamber C or of the member 13 whether the current traversing the fuse at the time be of the order of 5 or 15 amperes, these currents representing, for example, the minimum current which will slowly raise the heating device or furnace above the desired or safe temperature and the maximum heating current ordinarily used. 120

Inasmuch as conductors of different ma- 130

aterials melt or fuse at substantially predetermined different temperatures, and since it is often desirable that the circuit be opened upon attainment of a heater or furnace temperature which is different from the temperature of fusion of available fuse materials, it is generally impossible to choose a fuse of a material which may be subjected directly to the temperature at attainment of which it is desirable the circuit should be opened. By recourse to my invention, however, it is possible to locate the fusible element in such position or beyond such barrier that it will be subjected to a substantially lower temperature and yet, by co-action of the current traversing the fusible element, cause its fusion upon attainment of a predetermined temperature within the heating element or heating zone. So locating the fusible element has the further advantage that its material does not deteriorate, as by oxidation, scaling, deformation or other effects which would otherwise result if it were subjected directly to the temperature at which it is desired the circuit shall be ruptured.

For brevity in the appended claims it shall be understood that the term "outer face" designates the surface of the furnace wall nearest the fusible element.

30. What I claim is:

1. The combination with a heating device comprising an electric heating element and a wall, of a fuse in circuit with said element and disposed in position to absorb heat from said element substantially exclusively through said wall, said fuse having a cross section such that its temperature rise due to the current traversing it is less than its temperature rise due to the heat absorbed from said heating device.

2. The combination with a heating device comprising an electric heating element and a wall, of a fuse in circuit with said element and disposed in contact with the outer face of said wall in position to absorb heat from said element through said wall, said fuse having a cross section such that its temperature rise due to the current traversing it is less than its temperature rise due to the heat absorbed from said heating device.

3. The combination with an electric heating device comprising an electric heating element and a wall, of a fuse in the circuit of said element and engaging the outer surface of the wall to absorb heat from said element through said wall, said fuse having a positive temperature coefficient of resistance and a cross section such that its temper-

ature rise due to the current traversing it is less than its temperature rise due to the heat absorbed from said heating device.

4. The combination with an electric heating element, of a fuse in the circuit thereof, a wall through which heat is absorbed by said fuse from said heating element, a second outer wall remote therefrom, electric terminal structure to which said fuse is detachably connected, said fuse extending from said terminal structure toward said first wall and having a portion subjected to high temperature adjacent said wall, and means for supporting said terminal structure in said second wall, whereby said terminal structure does not attain a temperature preventing interchange of fuses while said heating element is at high temperature.

5. The combination with an electric furnace comprising an electric heating element and a wall, of a fuse in circuit with said element and disposed in engagement with the cooler side of said wall to absorb heat from said element through said wall, said fuse having such cross sectional dimensions and coefficient of resistance that it will rupture only within a comparatively small range of temperature variation within said furnace notwithstanding concurrent relatively large variations in current through said fuse and heating element.

6. The combination with an electric furnace comprising an electric heating element and a wall, of a fuse in circuit with said element and resiliently biased into positive heat conducting relation with the cooler side of said wall for absorbing heat from said element through the wall, and a heat insulated chamber coacting with said wall to substantially enclose the wall-contacting portion of said fuse, thereby concentrating heat upon said fuse portion.

7. The combination with an electric furnace comprising an electric heating element and a wall of refractory material, of an outer wall remote from and concentric with said first-named wall, a fuse in circuit with said heating element detachably supported on said outer wall and biased into resilient engagement with said first-named wall whereby heat absorbed by said fuse from said heating element, and to a much lesser degree heat due to the current through its own resistance, effects rupture of the fuse within a comparatively small temperature range of said furnace.

PAUL A. NEWMAN.
